CONCRETE-FORM-CLAMPING DEVICE

Application filed April 3, 1928. Serial No. 266,995.

This invention relates to adjustable clamping devices for retaining the walls of concrete pouring forms in desired assembled relation.

5 The invention has for its principal object to provide a novel arrangement of adjustable clamping devices having tightening wedges assembled therewith, said clamping devices being adapted to be mutually interlocked together in encircling relation to the form walls, and in such manner that the wedges thereof may be utilized to drive the same into tight gripping relation to said form walls.

10 15 The invention has for a further object to provide in connection with the clamp bars and their wedges a cooperating arrangement of holes possessing a vernier-like relation whereby the locking of the wedges in tightening position may be more efficiently attained.

The invention has for another object to provide means whereby a wedge device and clamp bar may be assembled in non-separable relation, while nevertheless leaving the wedge free for operative movement relative to the clamp bar.

20 Other objects of this invention, not at this time more particularly enumerated, will be clearly understood from the following detailed description of the same.

The invention is illustrated in the accompanying drawings, in which:—

Fig. 1 is a plan view of one arrangement 25 and construction of the adjustable clamping devices of this invention operatively related to assembled form walls, the latter being shown in horizontal section; Fig. 2 is a similar fragmentary plan view on an enlarged scale; and Fig. 3 is a sectional view taken on line 3—3 in said Fig. 2.

Fig. 4 is a fragmentary plan view of a modified construction and arrangement of 40 adjustable clamping devices, embodying the principles of this invention; Fig. 5 is a longitudinal section through the same, taken on line 5—5 in Fig. 4; and Fig. 6 is a transverse section, taken on line 6—6 in said Fig. 4.

45 50 Similar characters of reference are em-

ployed in the above described views, to indicate corresponding parts.

Referring first to Figs. 1 to 3 inclusive of the drawings, the reference character 10 indicates the form walls so arranged as to provide a mold or form of rectangular cross-section, such as would be employed in pouring concrete piers, columns and similar structures.

To retain a rectangular form of the kind above mentioned in position, a set of four mutually interengageable clamping devices made according to this invention would be required. Each such clamping device comprises a stretcher or bar 11 preferably made of flat steel. Rigidly connected with one end portion of each stretcher or bar 11, and in overlying parallel relation thereto is a clip member 12, the same being spaced from the body of the stretcher or bar 11 by a spacing block 13 interposed between the outer end thereof and the adjacent end of said stretcher or bar 11, and then rigidly secured in such relation by rivets 14, or any other suitable kind of fastening means. While the clip member 12 and stretcher or bar 11 may be assembled to provide a fabricated construction as above described, it will never the less be understood that the parts may be assembled in other ways, or the clip member may be made as an integral part of the end portion of the stretcher or bar if desired. When the clip member 12 and stretcher or bar 11 are arranged as described, a receiving socket or space 15 intermediate the same is provided in which the free end of an associated stretcher or bar 11 may be engaged when assembling the clamping devices in mutually interengaged operative relation. Assembled with each stretcher or bar 11, so as to be transversely movable through the rearward or inner portion of the receiving socket or space 15 intermediate the stretcher or bar 11 and its clip member 12, is a tightening wedge 16 having an oblique or inclined margin 17 at its outer side. The inner end of the spacing block 13, or equivalent portion bounding the inner end of the receiving socket or space 15, is formed to provide an oblique abutment 18 corresponding to the oblique side 17 of the wedge 16 and against

85 90 95 100

which the same thrusts when actuated. In order to retain the wedge in non-separable and yet operative relation to the stretcher or bar 11 with which it is associated I provide in the body of the wedge an opening or counter-sunk cavity 19 extending longitudinally thereof, and I provide in fixed relation to clip member 12, or other stationary part of the stretcher or bar structure, a keeper tongue or projection 20 which, when the wedge is assembled with the stretcher or bar, is entered in the opening or cavity 19 so that, while an adequate degree of free longitudinal movement is permitted to the wedge relative to the stretcher or bar, entire displacement or separation of one from the other is prevented by the engagement of said tongue or projection with the margins of said opening or cavity. Provided in the stretcher or bar 11 and its clip member 12 are a series of registered openings or perforations 21 extending in a transverse row. In the body of the wedge I provide a longitudinal row of openings or perforations 22, which are aligned to said openings or perforations 21 so as to be selectively registerable with the latter when the wedge is moved lengthwise. The openings or perforations 21 of the stretcher or bar structure are spaced closer together than are the openings or perforations 22 of the wedge, and consequently a vernier-like interrelation of the two said groups of openings or perforations is provided, whereby but slight relative movement of the wedge relative to the stretcher or bar structure will bring some one of the openings or perforations of the former into registration with one or the other of the set of openings or perforations of the latter, so that the wedge may easily be interlocked with the stretcher or bar structure, in substantially any position to which it may be adjusted when actuated, by inserting a retaining pin 23 through the registered openings. Said keeper pin 23 may consist of a nail, cotter-pin, or other suitable device. By this novel arrangement extremely delicate adjustment of the wedge in tightened position may be obtained, and when obtained the wedge may be securely retained against displacement therefrom. This vernier-like arrangement of the respective cooperating groups of the openings or perforations of the wedge and bar is one of the important novel elements of the instant invention. Each stretcher or bar 11 is provided, extending backwardly from its free end, with a longitudinal row of spaced openings or perforations 24.

When operatively assembling the clamping devices in encircling and holding relation to rectangularly disposed form walls 10, the series of stretchers or bars are arranged at right angles one to the other against the outer faces of said form walls 10, with the free end of one thereof engaged in the receiving socket 15 or space 15 of the next adjoining one thereof,

and so as to lie intermediate the abutting form wall and the wedge 16 of the latter, the wedges being withdrawn rearwardly to an initial position. When the parts are thus assembled relative to the form to be clamped thereby, holding pins 25 are inserted through an opening or perforation 24 at the outer side of an adjacent interengaged stretcher or bar 11 to prevent separation of thus interconnected clamping devices. When the parts are thus disposed, the clamping devices are ready to be finally tightened home in close gripping relation to the form walls. This latter operation is attained by driving home the wedges 16, thus taking up all slack in the encircling clamping devices and thereby securing a snug and tight gripping embracing relation of the latter to the form. When the wedges 16 are driven home to tightening position, the retaining pins 23 are inserted through the particular openings or perforations 21—22 which have been brought into alignment or registration, thus locking wedges against slipping and consequently holding the clamping devices against accidental displacement from operative interengaged relation to the form.

From the above description it will be obvious that the instant invention provides a very simple and yet highly efficient arrangement of mutually interengageable clamping devices for the purposes intended, and also of such construction that they may be very closely adjusted and then securely locked in the attained adjusted relation by reason of the novel vernier-like grouping of cooperating openings or perforations with which each stretcher or bar and its associate wedge is provided. Furthermore, the wedge of each stretcher or bar is retained against separation therefrom while yet being capable of adequate operative manipulation, and consequently impairment of the clamping devices by separation and loss of parts composing the same is avoided; this being a practical convenience of considerable advantage to the users of the devices.

Referring now to Figs. 4 to 6 inclusive I have shown therein a somewhat modified arrangement and construction of my novel clamping devices, which still embodies, however, the general principles involved in the present invention.

In this modified construction I have provided an arrangement whereby the stretchers or bars may be adjusted with reference to length thereof desired to be used in a given case. To this end I provide a stretcher or bar 11', on one end of which is slidably and adjustably mounted a sleeve 26 with which is connected the overlying clip member 12'. The stretcher or bar 11' is provided with a longitudinal row of spaced openings or perforations 27, and the sleeve 26 with a through opening 28 which may be selectively regis-

tered with one of said openings or perforations 27, according to the operative length of 5 stretcher or bar to be utilized; the sleeve being retained in the selected adjusted position by passing a lock pin 29 through the thus registered openings or perforations 27-28. If desired a stop member 30 may be furnished adjacent the rear end of the stretcher or bar 11' to prevent displacement of the sleeve 26 therefrom. The clip member 12' is spaced 10 from the stretcher or bar 11' so as to provide the receiving socket or space 15' in which the wedge 16' is disposed, and in which may be received the free end of a mutually cooperating adjacent stretcher or bar 11'. The wedge 16 is provided with the opening or 15 cavity 19' to receive the cooperating keeper tongue or projection 20' of the clip member 12', for the purposes already above mentioned, and also the free end portion of the 20 stretcher or bar 11' is provided with the longitudinal row of spaced openings or perforations 24' for the reception of holding pins 25'. The wedge 16' is provided with the longitudinal 25 row of spaced openings or perforations 22'. Inasmuch as the bar is movable through the sleeve 26, a modified arrangement is required for the location of the group of openings or perforations 21' which possess 30 the vernier-like cooperative relation to the wedge openings or perforations 22'; to satisfy this requirement I provide the sleeve 26 at one side with a laterally off-set tongue or arm 26' which overlies that portion of the wedge 16' occupied by the openings or perforations 22', and in this tongue or arm 26' are disposed the required openings or perforations 21' which cooperate with the wedge openings 22' for the reception of a retaining pin 23'.

It will be obvious from an inspection of the drawings, that aside from stretcher or bar adjustment features of the described modified arrangement of the clamping devices, that the same correspond substantially 45 in construction, arrangement, and mode of use to the first described structure; and, furthermore, all the advantages heretofore pointed out involved in the construction and use of the clamping device of said first described structure are inherent in the aforesaid modified structure.

I am aware that changes, other than those above mentioned, may be made in the general 50 arrangements and combinations of the various devices and parts, as well as in the details of the construction of the same, without departing from the scope of this invention as described in the foregoing specification, and 55 as defined in the appended claims. Hence, I do not limit my invention to the exact arrangements and combinations of the devices and parts as set forth in the foregoing specification, nor do I confine myself to the 60 exact details of the construction of said parts

as illustrated in the accompanying drawings.

I claim:

1. In a form clamping device, a clamp bar structure having means at one end to mount 70 a tightening wedge for operative movement relative thereto and means to receive the end of a cooperating clamp bar to dispose the same between said wedge and the form to

which the clamping device is applied, and 75 said wedge and said clamp bar structure having groups of cooperating retaining pin receiving perforations, said groups of perforations having a vernier-like relation one to the other.

2. In a form clamping device, a clamp bar structure having means at one end to mount 80 a tightening wedge for operative movement relative thereto and means to receive the end of a cooperating clamp bar to dispose the same between said wedge and the form to which the clamping device is applied, said wedge and said clamp bar structure having groups of cooperating retaining pin receiving perforations, said groups of perforations having a vernier-like relation one to the other and means for retaining the wedge in non-separable relation to the clamp bar structure.

3. In a form clamping device, a clamp bar structure having means at one end to mount 85 a tightening wedge for operative movement relative thereto and means to receive the end of a cooperating clamp bar to dispose the same between said wedge and the form to which the clamping device is applied, said wedge and said clamp bar structure having groups of cooperating retaining pin receiving perforations, said groups of perforations having a vernier-like relation one to the other 90 said wedge having a longitudinal cavity in its body, and a keeper tongue projecting from said clamp bar structure into said wedge cavity to retain said wedge in non-separable relation to said clamp bar structure.

4. In a form clamping device, a clamp bar structure having means at one end to mount 95 a tightening wedge for operative relation thereto and means to receive the end of a cooperating clamp bar to dispose the same between said wedge and the form to which the clamping device is applied, said wedge having a longitudinal cavity in its body, and a keeper tongue projecting from said clamp bar structure into said wedge cavity to retain 100 the wedge in non-separable relation to the clamp bar structure.

5. A form clamping device, comprising 105 mutually interengageable clamp bar structures adapted to be mounted in encircling 110 relation to a form to be held thereby, each clamp bar structure having at one end a receiving socket forming means having at one end thereof a wedge thrust abutment, a 115 tightening wedge movable endwise through 120

125

5 said socket forming means and against said thrust abutment, said receiving socket of one clamp bar structure being adapted to receive a portion of an adjacent clamp bar structure for disposition between said wedge and the form to which the clamping device is applied, 10 said wedge having a longitudinal cavity in its body, and a keeper tongue in fixed relation to a wall of said receiving socket for projection into said wedge cavity to retain said wedge in non-separable relation to said clamp bar structure with which it is assembled.

15 6. A form clamping device, comprising mutually interengageable clamp bar structures adapted to be mounted in encircling relation to a form to be held thereby, each clamp bar structure having at one end a receiving socket forming means having at one 20 end thereof a wedge thrust abutment, a tightening wedge movable endwise through said socket forming means and against said thrust abutment, said receiving socket on one clamp bar structure being adapted to receive a portion of an adjacent clamp bar structure for disposition between said wedge and the form to which the clamping device is applied, and said wedge and clamp bar structure with which it is assembled having 25 groups of cooperating retaining pin receiving perforations, said groups of perforations having a vernier-like relation one to the other.

30 7. A form of clamping device, comprising mutually interengageable clamp bar structures adapted to be mounted in encircling relation to a form to be held thereby, each clamp bar structure having at one end a receiving socket forming means having at one 35 end thereof a wedge thrust abutment, a tightening wedge movable endwise through said socket forming means and against said thrust abutment, said receiving socket on one clamp bar structure being adapted to receive a portion of an adjacent clamp bar structure for disposition between said wedge and the form to which the clamping device is applied, said wedge and clamp bar structure with which it is assembled having groups of cooperating retaining pin receiving perforations, said groups of perforations having a vernier-like relation one to the other, and means for retaining the inserted adjacent 40 clamp bar structure against withdrawal from said receiving socket means said wedge having a longitudinal cavity in its body, and a keeper tongue in fixed relation to a wall of said receiving socket for projection into said wedge cavity to retain said wedge in non-separable relation to said clamp bar structure with which it is assembled.

45 8. A form clamping device, comprising mutually interengageable clamp bar structures adapted to be mounted in encircling relation to a form to be held thereby, each clamp bar structure having at one end thereof a wedge thrust abutment, a tightening wedge movable endwise through said socket forming means and against said thrust abutment, said receiving socket on one clamp bar structure being adapted to receive a portion of an adjacent clamp bar structure for disposition between said wedge and the form to which the clamping device is applied, said wedge and clamp bar structure with which it is assembled having groups of cooperating retaining pin receiving perforations, said groups of perforations having a vernier-like relation one to the other, and means for retaining the inserted adjacent clamp bar structure against withdrawal from said receiving socket means.

50 9. A form clamping device, comprising mutually interengageable clamp bar structures adapted to be mounted in encircling relation to a form to be held thereby, each clamp bar structure having at one end thereof a wedge thrust abutment, a tightening wedge movable endwise through said socket forming means and against said thrust abutment, said receiving socket on one clamp bar structure being adapted to receive a portion of an adjacent clamp bar structure for disposition between said wedge and the form to which the clamping device is applied, said wedge and clamp bar structure with which it is assembled having groups of cooperating retaining pin receiving perforations, said groups of perforations having a vernier-like relation one to the other, and means for retaining the inserted adjacent clamp bar structure against withdrawal from said receiving socket means.

55 10. A form clamping device, comprising mutually interengageable clamp bar structures adapted to be mounted in encircling relation to a form to be held thereby, each clamp bar structure having at one end a receiving socket forming means having at one end thereof a wedge thrust abutment, a tightening wedge movable endwise through said socket forming means and against said thrust abutment, said receiving socket on one clamp bar structure being adapted to receive a portion of an adjacent clamp bar structure for disposition between said wedge and the form to which the clamping device is applied, said wedge and clamp bar structure with which it is assembled having groups of cooperating retaining pin receiving perforations, said groups of perforations having a vernier-like relation one to the other said wedge having a longitudinal cavity in its body, and a keeper tongue in fixed relation to a wall of said receiving socket for projection into said wedge cavity to retain said wedge in non-separable relation to said clamp bar structure with which it is assembled.

11. A form clamping device, comprising mutually interengageable clamp bar structures adapted to be mounted in encircling relation to a form to be held thereby, each clamp bar structure having at one end a receiving socket forming means having at one end thereof a wedge thrust abutment, a tightening wedge movable endwise through said socket forming means and against said thrust abutment, said receiving socket on one clamp bar structure being adapted to receive a portion of an adjacent clamp bar structure for disposition between said wedge and the form to which the clamping device is applied, said wedge and clamp bar structure with which it is assembled having groups of cooperating retaining pin receiving perforations, said groups of perforations having a vernier-like relation one to the other and means for retaining the inserted adjacent clamp bar structure against withdrawal from said receiving socket means said wedge having a longitudinal cavity in its body, and a keeper tongue in fixed relation to a wall of said receiving socket for projection into said wedge cavity to retain said wedge in non-separable relation to said clamp bar structure with which it is assembled.

12. In testimony that I claim the invention set forth above I have hereunto set my hand this 2nd day of April, 1928.

SAMUEL S. COLT.
